KNITTED SELVAGE CONSTRUCTION AND
METHOD THEREFOR

Hugo Hemmerich, Reinholds, Pa., assignor to
Berkshire Knitting Mills, Wyomissing, Pa., a
corporation of Pennsylvania

Application June 30, 1941, Serial No. 400,376

8 Claims. (Cl. 66—182)

This invention relates to knitted fabric and more particularly to flat-knitted full-fashioned hosiery blanks and the method of making the same.

In the manufacture of full-fashioned hosiery, of silk, "nylon" and other yarns, it is a well known practice to reinforce the heel sections with one or more reinforcing yarns or threads, the reinforcements usually extending to the edges of the blanks. This has been found objectionable in that it results in an increase in the thickness of the seam in the region of the heel to an extent causing discomfort to the wearer of the hosiery.

Further, it is a known practice to knit the leg and foot section of a stocking blank on one machine to make a "single unit" blank. One method of carrying out said practice involves widening the blank in the region of the heel. Such widening, however, has given difficulty in that usual selvage loop arrangements at these regions promote runs. This is particularly true when "nylon" yarn is used in the selvage construction, since such yarn is more slippery than silk.

It is an object of my invention to provide a flat knitted fabric, of which an example is a full-fashioned stocking blank, having a widened reinforced run interrupting region terminating in a single-yarn area along the seaming edges.

It is a further object of my invention to provide such a stocking blank having a widened reinforced section provided with a single-yarn non-run arrangement along the selvage edges.

Another object of my invention is to provide a single unit stocking blank having a widened reinforced heel section provided with a single yarn area along the edge including a loop formation for preventing runs.

An additional object is to provide a method of widening flat-knitted fabric or stocking blanks having one or more reinforced areas, the selvages of which are relatively thinner and formed of a loop formation impervious to runners.

A further object is to provide a full-fashioned stocking blank having a non-run seaming edge comprising increasing weights or numbers of yarns in the direction inwardly from the edge.

With these and other objects in view, which will become apparent from the following detailed description of the illustrative embodiments of the invention shown in the accompanying drawings, my invention resides in the novel knitted fabrics and method of making the same, as

hereinafter more particularly pointed out in the claims.

In the drawings:

Fig. 1 is a side elevational view of a stocking embodying my article invention and made according to my process invention;

Fig. 2 is a view of a blank from which the stocking of Fig. 1 is formed;

Fig. 3 is an enlarged detail view of one of the widened heel sections of the blank shown in Fig. 2;

Fig. 4 is a detail view of a straight edged portion of the heel portion shown in Fig. 3 and enlarged relative thereto;

Fig. 5 is a detail view of a widened portion of the heel portion shown in Fig. 3 and enlarged relative thereto;

Fig. 6 is a diagrammatic cross-sectional view taken substantially on the line 6—6 of Fig. 3;

Fig. 7 is an enlarged diagrammatic detail view of a widened part of a modified heel section within my invention;

Fig. 8 is a view similar to Fig. 7 of a further modified heel section; and

Fig. 9 is a view similar to Fig. 5 but showing the fabric of Fig. 8.

Referring to the drawings, a stocking A, Fig. 1, is one embodying my fabric invention and one made in accordance with my method invention. Stocking A is of a full-fashioned type, having been knitted in the form of a flat blank B, Fig. 2. The selvage edges of blank B were then seamed together along the seam line S to form the stocking A. The blank B is of the "single unit" type, that is knitted throughout on a single machine. I do not limit myself to this in all cases, however, as some aspects of my invention are equally applicable to stocking the blanks for which have been knitted on more than one machine, blanks made on the well known legger and footer machines being examples of another form to which my invention may be applied.

The blank B includes the usual two-ply welt portion 10 at its top followed by a single ply unreinforced portion 11 which may or may not include an after welt or shadow welt (not shown), corresponding portions 10 and 11 appearing in the stocking A. The usual fashioning marks 12 and 13 for the knee and leg narrowings are shown in the portion 11 of both the blank B and stocking A. Below the section in which the narrowing marks 13 appear, the single yarn or unreinforced portion extends down to include an ankle section 14 and also an instep section

15. The blank B has also a two yarn or reinforced area 16 of generally U shape extending from the toe along both sides of the instep area 15 into the lower end of the ankle section 14 where the spaced upper ends 17 of area 16 constitute high heel portions of the blank B and stocking A. In the blank shown, the heel portions proper 18 are widened in their upper parts along the lines 19, and narrowed in their lower parts along the lines 21, fashion marks 22 appearing in blank B and stocking A as the result of the narrowing operation. Heel portions 18 have also parts provided with straight parallel sides 23 connecting the inclined boundary lines 19 and 21. In the section bounded by the outwardly inclined lines or edges 18, the fabric is widened by racking out the end stops a distance of two needles at each end of certain courses. In knitting blank B, the end stops were racked out every fourth course. However, I do not limit myself to widening by two needles or at both ends of a given course.

Heel portions 18 of blank B include also narrow strips 24 as shown in Figs. 2 and 3, of the single yarn area 11 which extend along the outer sides of the two yarn area 16 in the heel portions 18 and form the selvage edges of the blank B along the lines 19, 21 and 23, strips 24 terminating at points 25 at the lower ends of the heel portions 18. The single yarn strip 24 along the edge portions 19 where widening is carried out, when of plain knitted loop formation as shown, is of a slip-loop character and has a tendency to run in case a loop is unsupported or a yarn breaks. This is especially true when the foot is made of "nylon" yarn. "Nylon" yarn being more slippery than silk it runs even more readily when made into slip-loop formations than silk. The edge of the two yarn area 16, however, acts as a run stop, keeping the runs in the single yarn selvage strips 24 and producing a single yarn selvage strip or area of an open character as best shown in Fig. 5. Owing to the action of the reinforced area 16 in blocking runs starting in the relatively light area or strip 24, all the fabric containing runs or being of an open character is easily taken into the stocking seam.

Along the parts of the heel portions 18 having straight or parallel edges 23, there is no more tendency for the single yarn area to develop runs than in the portion 11, and the single yarn strip 24 along the selvages remains intact as knitted as best appears in Fig. 4, except, of course, in case of a broken yarn.

Along the edge 21, conditions are the same so far as runs are concerned as along edge 23.

In the heel portions 18, further, a third yarn is employed producing three yarn areas 26. Areas 26 are entirely surrounded by parts of the two yarn area 16, narrow strips 27 of the two yarn section or area 16 lying between areas 26 and the single yarn selvage strips 24, and the area 16 also extending beyond the areas 26 on all other sides of the latter. As is clear from Figs. 1 and 2, fashion marks 22 caused by narrowing heel portions 18 lie within the triple yarn areas 26.

The relative weights or thicknesses and positions of fabric parts or sections 11, 16, 24, 26 and 27 are perhaps best understood from Fig. 6 in which the unreinforced or single yarn areas 11 and 24 are shown not only as extending on both sides of the portions 16 and 27 which are reinforced by a single yarn in addition to the

body yarn and the two yarn areas 16 and 27 are shown as extending on both sides of the portion 26 which is reinforced by two yarns in addition to the body yarn, the single yarn areas being shown in Fig. 6 as having minimum weight or thickness, the two yarn areas as having an intermediate weight or thickness and the three yarn area 26 is shown as having a maximum weight or thickness. The showing in Fig. 6 will be understood to be somewhat diagrammatic since the difference in thickness between the different areas is small. However, I do not limit myself to an arrangement in which a lighter weight area entirely surrounds a heavier area, but considered as within my invention any arrangement in which a heavier area is largely embraced by a lighter one.

The single yarn selvage strips 24 are knitted only two needles wide, and this is also true of the two yarn strips 27 which are contiguous thereto and on the inner sides thereof. Consequently, the strips 24 are caught within the seam when the blank B is seamed to produce the stocking A, so that the fact that loops may have dropped out is not necessarily critical.

However, it has been found to be preferable that the selvages be free, in the widened areas as in others, of any marked tendency to develop runs and I have discovered a loop formation and method of making it which widens a plain knitted fabric while resulting in a selvage which is substantially run-proof. A part of a heel portion 18A of a single unit stocking widened by the use of said loop formation is shown in Fig. 7. The heel part 18A is shown as including a single yarn selvage strip 24A, two needle wales wide, and a two yarn strip 27A, also two needle wales wide, between the edge 18A and the three yarn portion or area 26A. In making the widened part shown in Fig. 7, widening was performed every fourth course although it may be performed more or less often if desired, depending on the style of stocking. The said widening operation in a given course includes spreading each of the needle loops *a* at the edge of the fabric outward so that it surrounds two needles, the needle on which it was formed and one on the outside of said needle. The spreading of the end needle loops of the course is followed by the operation of moving the end stops for the yarn carrier rods and the yarn carrier rods themselves outwardly. Preferably, the stops are moved out two needles at each end of a given course, the rods being moved an equal distance at approximately the same time, but I do not limit myself to moving the stops more than one needle at each end in a given course as the stops may be moved out one needle in the course in which the loops are spread outwardly and another needle in the next course, especially when widening is performed only every fifth course. Moreover, the stops may be moved out alternately at opposite edges of the fabric in either one needle steps or two needle steps. As the result of the spreading of a loop *a* and moving out the yarn carrier rod two needles, an end needle loop *b* is formed in the next course, beginning a needle wale on the outside of the one in which loop *a* was formed. In the course next following the one in which loop *b* was formed, several bights of yarn interwine as a result of the knitting operation, following the stepping out of the end stops, to form a nucleus *c* serving as a support for needle loop *d* in a wale outside the whale of needle loop *b* in the next following course, the third course after the one in which loop *a* was spread. In

the fabric shown in Fig. 7, another loop *a* is spread outwardly in the same needle wale as loop *d* in the course following the one containing loop *d*, thereby beginning another repeat of four courses in which the fabric is widened by two needle wales at each edge, i. e. four needles in all. In each instance in which a loop *a* is spread at the edge of the fabric it is preferred to spread the two loops contiguous thereto in the same course in the same direction as loop *a*, the lower outer edge of the needle loop *e*, next to loop *a*, serving to support a sinker loop *f* on the inside of needle loop *b* and in the same course, so that the loop *b* has the usual form of the ordinary plain knitted loop. The loop *g* is also spread as shown in Fig. 7, loop *g* lying next to loop *e* but in the section 27A. While it is preferred to spread three loops at each edge of the fabric, I do not limit myself to this. The single yarn strips 24 and 24A, especially in conjunction with the two yarn strips 27 and 27A, materially reduce the bulkiness of the seams formed when the edges of the blank B and the like are sewed together, although some of the three yarn area 26A is sometimes caught into a seam.

In order to avoid practically all chance of catching any of a three yarn area 26 into a seam, I have shown in Figs. 8 and 9 a portion of a heel section of a stocking which is similar to that shown in Fig. 7 except that it includes a single thread selvage strip 24B which is four needle wales wide instead of only two and that the two-yarn strip 27B between the strip 24B and the three yarn section 26B consequently contains no spread loops such as loop *g* in Fig. 7. The arrangement of Figs. 8 and 9 therefore has six needle wales, four in strip 24B and two in strip 27B, between each three-yarn section or area 26B and the selvage edge 19B of the fabric, and there is no need of catching any of the three yarn area into the seam. In fact, with care, a seam can be limited almost entirely to the single yarn strips 24B.

It will be seen that by providing a relatively light or thin area or light areas along the seaming edge, I obtain a relatively light or fine seam. Also, by stopping a reinforcing thread short of a seaming edge, a thread arrangement is obtained acting as a barrier or run stop along the edge of the reinforced area. Further, by spreading three loops in each widened course, I can obtain a substantially run-proof light weight selvage.

Of course, the improvements specifically shown and described by which I obtain the above results, can be changed and modified in various ways without departing from the invention herein disclosed and hereinafter claimed.

I claim:

1. A flat knitted article including a reinforced section and a single yarn area along the outer edge of said reinforced section of a width adapted to be taken into a seam, said single yarn area

including a run-stop loop formation and said reinforced section adapted to stop runs originating in said single yarn area.

2. A stocking blank having a portion comprising a single yarn area extending along a selvage edge and in part of a slip-loop character, and a reinforced area largely embraced by said single yarn area and a three yarn area largely embraced by said two yarn area.

10 3. A stocking blank as set forth in claim 2 and in which the single yarn area along the selvage edge of the portion in contact with the two thread area is four needle wales wide.

15 4. A knitted fabric having a widened portion comprising a single yarn area extending along the edge, a two yarn area largely embraced by said single yarn area and running close to the widened edge and a three yarn area largely embraced by said two yarn area.

20 5. A knitted fabric having a section widened by loops in certain courses spread outwardly to cover two wales, said courses having loops spread similarly in a plurality of contiguous needle wales beginning with the ones at the ends of the courses, and having, in the third course from 25 each of those containing said spread loops, an additional wale outside the outer wale of the next preceding one of the courses containing spread loops; to further widen the fabric, a sinker loop in each course following one including spread loops engaging only in the outwardly stretched portion of a spread needle loop from an interior wale.

30 6. A knitted fabric having a widened section including a single thread area four needle wales wide along its selvage edge, said section being widened in every fourth course by spreading three contiguous needle loops to include wales outside of those in which they were formed.

35 7. A knitted fabric having a widened section including a single thread area a plurality of needle wales wide along its selvage edge, said section being widened in every fourth course by more than one contiguous needle loop each 40 spread outwardly to include at least two wales.

45 8. A knitted fabric having a single thread section, a plurality of needle wales wide, widened by loops in certain courses spread outwardly to cover two wales, said courses having loops spread similarly in a plurality of contiguous needle wales beginning with the ones at the ends of the courses, and having, in a course more than the second from each of those containing said spread loops, an additional wale outside the outer wale of the next preceding one of the courses containing spread loops to further widen the fabric, a sinker loop in each course following one including spread loops engaging only in the outwardly stretched portion of a spread needle loop from an interior wale.

HUGO HEMMERICH.
